(57) CLAIM

The ornamental design for a clasp for handbag, as shown and described.

DESCRIPTION

FIG. 1 is a bottom perspective view of a clasp for handbag showing my new design;

FIG. 1A is a cross-sectional view thereof;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof; and,

FIG. 8 is a bottom perspective view thereof, shown in the environment of a clasp for handbag.

The shadows and reflections in the photos form no part of the claimed design.

The broken line showing of the body of the handbag and portions of the clasp in the drawings shows unclaimed subject matter.
